UNITED STATES PATENT OFFICE.

WILBUR A. GROVER, OF MENOMONIE, WISCONSIN,

GAS BURNER.

Application filed June 17, 1924. Serial No. 720,489.

To all whom it may concern:

Be it known that I, WILBUR A. GROVER, a citizen of the United States, residing at Menomonie, in the county of Dunn and State 5 of Wisconsin, have invented certain new and useful improvements in Gas Burners; and I do hereby declare the following to be a full, clear, and exact description of the invention, such as will enable others skilled in the art 10 to which it appertains to make and use the same.

This invention relates to a liquid fuel burner, and particularly to such a burner having gas generating means therein. Such 15 burners are now commonly used in domestic stoves and ranges and also in connection with domestic furnaces.

It is an object of this invention to provide a burner of simple and efficient construction having a series of burner tubes, a portion or all of which may be burned at one time.

It is a further object of the invention to provide a burner having a plurality of 25 burner tubes, a generator tube disposed above the burner tubes through which the liquid fuel is passed, which generator tube is filled with finely divided metal such as brass filings.

It is also an object of the invention to provide a burner having a plurality of spaced parallel burner tubes connected at their ends to supply conduits which are connected to one side of a mixing chamber, said 35 mixing chamber being connected to a generating tube disposed over the burner tubes, which generating tube is provided with a plurality of fine screens.

These and other objects and advantages 40 of the invention will be fully set forth in the following description made in connection with the accompanying drawings in which like reference characters refer to the same parts throughout the different views, and in 45 which,

Fig. 1 is a plan view of the device, certain portions being broken away and others shown in horizontal section;

Fig. 2 is a view in side elevation of the 50 device also having certain parts broken away and other parts shown in vertical section;

Fig. 3 is a vertical section taken on the line 3-3 of Fig. 1, as indicated by the arrows;

Fig. 4 is a vertical section taken on the

line 4-4 of Fig. 2, as indicated by the arrows;

Fig. 5 is a view in side elevation of a spacing ring used; and

Fig. 6 is a view of a screen used in the 60 burner.

Referring to the drawings, a supply pipe 1 is shown which will be connected to an oil supply tank or means so that oil will be fed thereto by gravity or pressure. Said pipe 65 1 is connected by a suitable union member 2 to a generating tube 3 extending horizontally, which tube has disposed therein a considerable distance from the member 2, a reduction union or nipple 4. A portion 3^a 70 of the generating tube 3 extends from the reduced end of the nipple 4 and is laterally curved substantially in a semi-circle and connected to one side of a mixing chamber 5, a set screw 6 holding the portion 3^a in a 75 reduced extension 5^a of said mixing chamber. The nipple 4 has a shoulder formed therein and plurality of fine mesh screens 7 are disposed in said nipple, said screens being spaced by small rings 8 disposed therebetween. The screen in one end abuts said shoulder in the nipple 4 and the screen at the other end engages the end of the leg portion of generating tube 3 which holds the screens in proper position. The screens 7 80 preferably are progressively of finer mesh toward the portion 3^a. The portion of the generating tube 3 between members 2 and 4 preferably is filled with finely divided metal such as brass filings. The portion 3^a has its 85 end which is disposed in the mixing chamber 5 closed save for a small discharge opening 3^b and said end also has disposed therein a plurality of fine mesh screens 9 spaced by suitable spacing rings 10 similar to the rings 95 8 already described. The mixing chamber 5, as shown in Fig. 3, comprises a hollow member preferably of cast form having a downwardly extending open-ended portion 5^b. A conduit 11 extends from the side of mixing 100 chamber 5 opposite the portion 3^a, being held in a projection 5^c at one side of the mixing chamber by a set screw 12. The conduit 11 is connected by an elbow 13 to a T member 14 disposed some distance below the conduit 105 11. Pipes or conduits 15 and 16 extend, respectively, from the ends of T member 14 in opposite directions and have their ends bent substantially at right angles to extend 110 in spaced parallel relation, which ends are

closed by suitable plugs 17 and connected by a plate 18 extending therebetween, said plate being connected to the plugs 17 by headed screws 19. A small plate or bracket 5 connects conduit 15 to the union 2 and forms a support for the latter and pipe 1. A valve 20 is mounted in the conduit 16 adjacent the T 14 equipped with an operating handle 21 projecting upwardly through the conduit 16. A plurality of spaced parallel tubes 22 extend between parallel portions of the conduits 15 and 16. The tubes 22 are provided with spaced transverse slits 22^a extending across substantially the top half of said tubes. These conduits thus form supply conduits or headers for the tubes 22. It will be noted that the tubes 22 are thus parallel to the generator tube 3 and disposed some distance below the same. The burner tubes 22 are closed at their central portions. While the said tubes may be closed or projected in any desired manner, in the embodiment of the invention illustrated, the same are shown as formed of two sections divided 20 at their central portions and each threaded onto the opposite ends of a nipple 23, which nipple has therein a plug 24.

In operation, the tube 3 will preliminarily be heated in any desired manner and the oil will then be supplied through the pipe 1. This oil will pass into the generating tube 3 and will be vaporized by coming in contact with the hot walls of said tube and the heated metal therein. A gas will thus be generated, which gas will pass through the screens 8, through the portion 3^a, through the screens 10 and will issue through the opening 3^b into the mixing chamber 5. Air will enter through the lower portion 5^b of the mixing chamber and be mixed with this gas to form a combustible mixture. This mixture will pass through the tubes 15 and 16 and into the tubes 22 and will issue through the slits 22^a in said tubes.

The mixture issuing from the slits 22 will be ignited and the burner thus placed in operation. The flames rising from the burner tubes 22 will continue to heat the generating tube 3 so that the gas will continuously be generated and supplied to the burner tubes as long as the supply of oil is maintained. If it be desired to burn only a portion of the tubes 22, the valve 20 may be turned to close the conduit 16 and the tubes connected to the conduit 16 will then be turned off.

From the above description it is seen that applicant has provided a very simple and efficient liquid fuel burner. The necessary gas is quickly and efficiently generated in the tube 3 having the brass filings therein. The gas is cleaned by passing through the screens 8 and 9 and any solid matter prevented from being drawn into the mixing chamber 5.

An efficient mixture is formed in the mixing

chamber 5 and this chamber is sufficiently removed from the burner tubes to prevent any back firing. The burner is easily and cheaply constructed and the same has been found to be very successful in practical operation.

It will, of course, be understood, that various changes may be made in the form, details, arrangement and proportion of the parts without departing from the scope of applicant's invention, which, generally stated, consists in a device such as shown and described and set forth in the appended claims.

What is claimed is:

1. A liquid fuel burner comprising a liquid supply conduit, a generating tube connected thereto, a mixing chamber to which said generating tube is connected, gas supply conduits connected to said mixing chamber and extended in opposite directions parallel with said generating tube, said conduits being bent at right angles to extend in parallel relation, and a plurality of spaced parallel burner tubes connecting said parallel portions of said conduits and disposed beneath and parallel to said generating tube.

2. The structure set forth in claim 1, said mixing chamber and said conduits being disposed at one side of said generating tube and connected thereto by a curved portion, and a plurality of fine mesh screens disposed at each end of said curved portion.

3. A liquid fuel burner comprising a liquid supply conduit, a generating tube connected thereto, a mixing chamber to which said generating tube is connected, gas supply conduits connected to said mixing chamber and having parallel end portions extending at right angles to said generating tube, and a plurality of spaced parallel burner tubes connecting said parallel portions of said gas supply conduits and parallel to and disposed beneath said generating tube.

4. An oil burner comprising an oil supply conduit, a generating tube connected thereto, a mixing chamber disposed at one side of said generating tube, said generating tube having a laterally extending portion connected to said mixing chamber, oppositely extending conduits connected to said mixing chamber and disposed at one side of said generating tube parallel thereto, said conduits being bent at right angles to extend in parallel relation transversely of said generating tube, and a plurality of spaced burner tubes connecting said parallel portions of said conduits, said burner tubes being closed at their central portions, and means for controlling one end of all of said burner tubes.

In testimony whereof I affix my signature.

WILBUR A. GROVER.
